CLAIM

The ornamental design for a computer keyboard housing, as shown and described.

DESCRIPTION

FIG. 1 is a top plan view of a computer keyboard housing showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a bottom plan view thereof; and

FIG. 7 is a top, front, left side perspective view thereof.

FIG. 1

FIG. 3

FIG. 5

FIG. 2

FIG. 4

FIG. 7
